UNITED STATES PATENT OFFICE.

DAVID TURTLE AND MARK KLITENICK, NEW YORK, N. Y.

METAL CUTTER.

Application filed March 25, 1924. Serial No. 701,816.

This invention relates to metal bar cutting machines or devices and more particularly to a novel and improved mechanism for cutting either lead or brass bars as used by typesetters.

One of the objects of our invention is to provide a manually operable metal bar cutting device whereby extreme accuracy may be had in cutting metal bars according to predetermined measurement and particularly small inserts for filling in the type as used in the printing art.

Another object of our invention is to provide a mechanism of the above character wherein either lead or brass bars may be cut with rapidity and with extreme accuracy including a pair of adjustable gauges, movable relative to a cutter whereby both long and short pieces or strips of the metal may be easily cut with rapidity and as desired.

A further object of our invention is to provide a metal bar cutting mechanism including a novel and improved micrometer gauge and a graduated, stationary measuring rule, on which the gauge may be adjusted so that the desired length of metal bar or slug may be easily cut by the typesetter.

Another object of our invention is the provision of a metal bar cutting mechanism having a graduated rule and adjustable gauge slidable thereon, movable relative to a stationary cutter.

To enable others skilled in the art to fully comprehend the underlying features of our invention that they may embody the same in the various modifications in structure and relation contemplated, drawings depicting a preferred form have been annexed as a part of this disclosure and in such drawings, similar reference characters denote corresponding parts throughout all the views, of which,

Figure 1 is a plan view.

Figure 2 is a side view, the lever being shown partly in section.

Figure 3 is a view taken on the line 3—3 of Figure 2.

Figure 4 is a view taken on the line 4—4 of Figure 2.

Figure 5 is a detail view taken on the line 5—5 of Figure 2.

Figure 6 is a vertical section taken substantially on the line 6—6 of Figure 2.

Figure 7 is a view taken on the line 7—7 of Figure 2.

Figure 8 is an enlarged view, showing the relation of the end rule and the micrometer gauge in its relation to the cutter and,

Figure 9 is a further view showing the relation of the cutter knives.

Referring now to the drawings wherein like reference characters designate corresponding parts throughout the several views, 5 designates a flat plate or bed, which rests 65 on a flange support 6 and a substantially wide casting 7. The plate 5 supports a central, longitudinally extending, narrow bar 8 as a guide for the strip of metal to be cut when placed upon the bed above referred 70 to. The bar 8 carries a graduated metal rule, the edge of which is serrated at 10 for cooperation with an adjustable stop or abutment designated in its entirety by numeral 11. The lower portion 12 of the stop is provided with a recess so as to permit of the adjustment thereof across the face of the graduated metal rule 9, on which it is adapted to slide. The stop is also provided with a lever 13, pivoted at 14, the lower end of 75 said lever having a serrated face 15, which cooperates with the serrations 10 on the rule 9 so as to lock the stop in the desired position. A coil spring 16 is interposed between the upper end of the lever 13 and the 80 top or head of the stop and normally maintains the serrated face of said lever in engagement with the rule. By depressing the lever 13 against the resistance of the spring 16, it will be seen that the stop may be thus 85 moved to any desired position as clearly suggested by Figures 4 and 5 of the drawings. The stop 11 is also provided with two horizontally extending screws 17, 18, which are adapted to act as abutments for the ends 90 of the metal bar which is to be cut by the knife. The enlarged heads 18^a of the screws 17, 18, may be adjusted with respect to graduations 18^b on the stop 11 thereby accurately 95 regulating to a very small degree, the width 100 of a piece of metal desired.

Referring in particular to Figure 3 of the drawings, it will be seen that the top face of the casing 7 is undercut to receive the front end of the bed or plate 5 and that the stationary blade or knife 18^c is secured by screws 19 so that the said blade lies at right angles and flush with end and top surface of the bed or plate. The casting 7 also carries a short stub shaft 20 which pivotally supports the knife carrying arm 21, the front end 22 of which is curved downwardly and

constitutes a stop which engages an L-shaped extension 23 of the casting 7. Attached to the inner face of the arm 21 is the movable knife or blade 24 having a knife cutting edge 25 and recesses 26, said recesses affording sufficient clearance for the movable screws or stops of an adjustable gauge subsequently to be referred to.

The support 7 is formed with a vertical extension 28 to which the lever 29 is pivoted as indicated by numeral 30, said lever being in turn connected by the links 31, 32 attached to ears 30^a on the movable arm 21. A spring 34 within the movable arm 21, normally retains said arm in its raised or elevated position as shown by Figure 3.

Reference being had now to Figures 2 and 8 of the drawings, we have shown a second but shorter graduated, metal rule 35 secured by suitable screws 36 at one end thereof, to the casting 7 and preferably in alignment with the rule 9 on the bed or plate 5. The last mentioned rule 35 is provided with serrations 37 on the bottom face thereof, which cooperate with the serrated end 37^a of a lever 39, pivoted at 39^a to an adjustable gauge, designated in its entirety by numeral 40. A spring 41 interposed between the opposite end of the lever 39 and the gauge, normally retains the said lever in engagement with the serrated surface 37 of the rule as clearly shown by Figure 6 of the drawings. Consequently, by depressing the lever 39 against the resistance of the spring 41, the gauge may be moved to any desired position with respect to the graduated face 42.

The top of the gauge 40 is provided with a wedge shaped slot therein for receiving a wedge plate 43, which carries a yoke 44, the arms of the yoke 44 being adapted to support a pair of adjusting screws 45 whereby very fine adjustments may be made in that the heads of the screws constitute stops for the ends of the metal bars when the gauge 40 is moved in proximity to the cutting knives. On the other hand, the wedge-shaped plate is provided with a vertical aperture for receiving the pin 47 of a disc 48, said pin movable in the slot 49 and rotatable by the knurled nut 50. Consequently, as the nut is rotated, the wedge may be moved to different degrees on the graduated scale 40^a which advances or retards the heads of the adjustable screws 45 with respect to the cutter. A wedge locking member 52, having a locking lever 53 pivoted as at 54, is adapted to engage the side of the wedge plate to lock the same in its adjusted position, it being understood that the nut 50 carries a pin movable over the graduated face 40^a on the plate 43 whereby the adjustment may be set.

In order to prevent the bending or the curvature of the metal strip being cut be-

yond the cutting blade, we have provided a rest or support in the nature of an L-shaped pivoted member 56 mounted on a short shaft 57, extending outwardly from the casting 7, the longitudinally extending, 70 flat bar 58 being adapted to rest on the yoke 44 and between the adjustable screws 45, it being noted that the bar 58 is in longitudinal alignment with the rule 9, being immediately above the opposite rule 35 as clearly shown 75 by Figure 8 of the drawings. Under certain conditions, the rest or support 58 may be used as when longer pieces of metal are to be cut, but when very short pieces are desired, the rest may be thrown back on its 80 pivot or the shaft 57, in the manner shown by Figure 1 of the drawings.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the appended claims.

Having thus described our invention what we claim as new and desire to secure by United States Letters Patent is:— 95

1. In combination with the serrated edge rulers of a metal cutter, an adjusting stop slidable on one of said rulers, said stop comprising a vertical body having a longitudinal slot in the bottom thereof cooperating with said ruler, a spring controlled lever pivoted to the body, the lower, inner face of said lever having serrated teeth adapted to engage the serrated edge of the ruler whereby said stop may be set at predetermined positions, and a micrometer gauging stop associated with the other one of said rulers. 100

2. In combination with the serrated edge rulers of a metal cutter, an adjusting stop slidable on one of said rulers, said stop comprising a vertical body having a longitudinal slot in the bottom thereof cooperating with said ruler, a lever pivoted to the outer face of said stop, said lever having serrated teeth on the lower inner face thereof adapted to engage with the serrated teeth of the ruler, and a spring interposed between the upper end of the lever and said body to normally maintain the serrated teeth in engagement, a stop on the other ruler, a yoke carried by said stop, and adjusting screws in said yoke. 110

3. In combination with the serrated edge rulers of a metal cutter, an adjusting stop slidable on one of said rulers, said stop comprising a vertical body having a longitudinal slot in the bottom thereof cooperating with said ruler, a spring controlled lever having serrated teeth on the lower in- 125

ner face thereof cooperating with the teeth of the ruler and adjusting screws within the inner end of the stop constituting abutments for the ends of material to be cut, 5 a stop on the other of said rulers, and micrometer adjusting members carried by said last mentioned stop.

4. In combination with the serrated edge ruler of a metal cutter, an adjusting stop 10 comprising a slotted body slideable on the ruler, a pivoted, spring held lever having

serrated teeth adapted to engage the teeth on the ruler, an adjusting wedge and yoke carried thereby movable in the top of the body, adjusting screws movable with respect to the yoke, and means for locking the said yoke to the body when the screws are adjusted. 15

In testimony whereof we affix our signatures.
